HAIR RINSING AND WASHING SPRAY

Lester O. Jacobs, Monterey, Calif.
(761 Pershing Ave., San Jose, Calif. 95126)

Filed Sept. 5, 1968, Ser. No. 13,403

Term of patent 14 years

Int. Cl. D23—01

U.S. Cl. D23—6

FIG. 1 is a perspective view of a hair rinsing and washing spray showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a cross-sectional view taken in the plane indicated by the line 7—7 in FIG. 2.

The fragmentary broken line showing of a faucet in FIG. 1 is for purposes of illustration only.

I claim:

The ornamental design for a hair rinsing and washing spray, as shown and described.
